UNITED STATES PATENT OFFICE.

PAUL GFROERER, OF EVANSTON, ILLINOIS, ASSIGNOR OF ONE-HALF TO
NICKOLAS P. HOFFMANN, OF SAME PLACE.

BRIDGE-GATE.

SPECIFICATION forming part of Letters Patent No. 643,407, dated February 13, 1900.

Application filed April 5, 1899. Serial No. 711,781. (No model.)

To all whom it may concern:

Be it known that I, PAUL GFROERER, of Evanston, in the county of Cook and State of Illinois, have invented a new and useful Improvement in Bridge-Gates, of which the following is a description, reference being had to the accompanying drawings, which are a part of this specification.

My invention has relation to improvements in bridge-gates.

The invention pertains to the class of bridge-gates wherein the gates are automatically closed by the opening of the swinging bridge and automatically opened by the closing of the bridge, the primary object had in view being to provide a construction which is applicable either to a swinging bridge which makes one-half of a complete revolution or to a bridge which swings around in a complete circle, the gates being automatically opened and closed in the case of either of the forms of swinging bridges mentioned.

With the above primary object in view the invention consists of the devices and parts or their equivalents, as hereinafter more fully set forth.

Referring to the drawings, Figure 1 is a plan view of so much of one end of a swinging bridge and its abutment as is necessary to illustrate the application of my invention, the gate-arms being shown as closed and the bridge in the act of swinging toward a closed position in order to open the gate. Fig. 2 is an end elevation of abutment, showing the gate closed. Fig. 3 is an under view of Fig. 1. Fig. 4 is a cross-sectional view on the line 4-4 of Fig. 3, and Fig. 5 is an end elevation of the bridge.

Referring to the drawings, the numeral 6 indicates a swinging bridge, the end of which is shown as curved in the arc of a circle, and said end is formed or provided on its under side and at a medial point with a short rack 7.

The numeral 8 indicates the bridge-abutment, the end thereof which is contiguous to the end of the bridge being curved in a corresponding arc of a circle. Journaled in suitable bearings beneath the bridge-abutment and extending longitudinally thereof are parallel shafts 9, each shaft having mounted thereon at a point between its ends a gear

wheel 10, the two gears being in mesh. The outer extremities of the shafts have mounted thereon pinions 11 11', which are not in mesh. Also mounted on the shafts 9 are sprocket-wheels 12 12. Short shafts 13 13 are mounted in suitable bearings just beneath the side edges of the bridge-abutment, and these shafts have mounted thereon sprocket-wheels 14 14, which are connected to the sprocket-wheels 12 12 by means of sprocket-chains 15 15. Extending upwardly from the side edges of the bridge-abutment are standards or uprights 16 16. The upper ends of these standards form bearings for shafts 17 17, and one end 65 of each of these shafts carries a sprocket-wheel 18. Each sprocket-wheel 18 is connected to another sprocket-wheel 19 on each shaft 13 by means of a sprocket-chain 20. The shafts 17 also carry arms 21 21, which 70 form the gate. The outer ends of these arms have extending therefrom rods 22 22, upon which are adjustably mounted counterbalancing-weights 23 23.

It will of course be understood that the end 75 of the bridge not shown in the drawings is constructed in a similar manner to the end which is illustrated and specifically described—that is to say, it is provided with a rack similar to the rack 7. The opposite 80 bridge-abutment (not shown) is also constructed exactly similar to the one herein illustrated and described.

When the bridge is at a closed position, the rack 7 at each end is between and in engagement with the pinions 11 11', and the arms forming the gates are at the raised position shown in Fig. 4. If now the bridge is swung toward an open position—say the end of the bridge shown in Fig. 1 toward the left—the 90 rack 7 at that end of the bridge will act on the pinion 11' and cause a rotation of the shaft 9, carrying said pinion in one direction. This rotation of said shaft 9 will be communicated to the other shaft 9 by reason of the intermeshing gears 10, and said other shaft 9 will be caused to rotate in an opposite direction. The shafts 9 so rotated will of course cause an actuation of the sprocket-chains 15, and these chains, acting on the sprocket-wheels 14, will cause rotation of said sprocket-wheels, and this rotation will be communicated to the

shafts 13 13. The rotation of the shafts 13 will be communicated to the short shafts 17 at the upper ends of the standards, and as the arms 21 are carried by these short shafts 5 17, said arms will be turned downwardly to a closed position. At the opposite end of the bridge the same action takes place, the rack 7 at that end acting on the counterpart of the pinion 11 and of course operating to produce a similar action—viz., the closing of the arms 21.

If the bridge had only been swung around in a half-circle to an open position and the end shown in Fig. 1 is then swung around to 15 the right toward a closed position, the rack 7 at the left-hand end of the bridge will act on the pinion 11' and through the described connection will cause an upturning or opening of the arms 21, the rack finally seating 20 itself between the two pinions 11 11'. The rack 7 at the right-hand end of the bridge on this swinging of said bridge will act on the counterpart of the pinion 11 and cause an upturning of the arms 21 of the other bridge- 25 abutment in exactly a similar manner.

If the end of the bridge shown in Fig. 1 instead of being swung around to the right toward a closed position is swung toward the left, the rack 7 at the left-hand end of the 30 bridge will engage the pinion 11 and the rack 7 at the right-hand end of the bridge will engage the pinion 11' which, will of course effect the opening of both sets of arms 21.

If the bridge, after having been opened by 35 making a half-turn, is closed by completing the circle of revolution, the left-hand end of the bridge (shown in Fig. 1) is brought around to the right-hand abutment, and the rack 7 of said end of the bridge is brought into engagement with the pinion of the right-hand abutment corresponding to the pinion 11' and the arms 21 thereby turned upwardly in the manner described, while the right-hand end of the bridge is brought around to the 40 left-hand abutment, and the rack 7 of said right-hand end is brought into engagement with the pinion 11 to cause the uplifting of the arms 21.

Of course instead of opening the bridge by 45 swinging it toward the left, as first described, it may be opened by swinging it toward the right. In such case the rack 7 of the left-hand end of the bridge would engage with the pinion 11 to effect the closing of the left-hand gate, while the rack 7 of the right-hand

end of the bridge would engage the pinion corresponding to the pinion 11' to effect the closing of the right-hand gate.

From the above description it will be seen that my invention is adapted to close the 60 gates of the opposite bridge-abutments no matter in what direction the bridge is swung open and to also close the gates no matter in what direction the bridge is swung to a closed position. The construction also adapts the 65 gates to be closed and opened by a bridge which is constructed to swing in a complete circle.

What I claim as my invention is—

1. The combination, of a swinging bridge, 70 a bridge-abutment, longitudinal shafts journaled in the bridge-abutment and parallel and in close proximity to each other, said shafts being geared together, pinions carried by the longitudinal shafts and arranged close to each 75 other but not in meshing engagement, a short rack carried by the swinging bridge and adapted to rotate one or the other of the pinions, in accordance with the direction in which the bridge is swung, outer shafts journaled in the bridge-abutment, means for transferring the rotation of the first-mentioned shafts to the outer shafts, uprights or standards, shafts journaled therein, gate-arms carried by said shafts, and means for 80 transferring the rotation of the outer shafts to the bridge-arm shafts.

2. The combination, of a swinging bridge provided with an end rack, a bridge-abutment, longitudinal shafts journaled in said 90 bridge-abutment, said shafts being geared together, and provided on their outer ends with non-meshing pinions, and near their inner ends with sprocket-wheels, outer shafts having sprocket-wheels mounted thereon, 95 sprocket-chains connecting said sprocket-wheels with the sprocket-wheels of the longitudinal shafts, uprights or standards, shafts journaled therein, and having sprocket-wheels mounted thereon, sprocket-chains connecting said sprocket-wheels with sprocket-wheels of the outer shafts, and gate-arms carried by the shafts of the uprights or standards. 100

In testimony whereof I affix my signature in presence of two witnesses.

PAUL GFROERER.
